UNITED STATES PATENT OFFICE.

FRANK E. PFISTER, OF OAKLAND, CALIFORNIA.

GAS-GENERATOR FOR EXPLOSIVE-ENGINES.

SPECIFICATION forming part of Letters Patent No. 759,011, dated May 3, 1904.

Application filed March 16, 1903. Serial No. 147,909. (No model.)

To all whom it may concern:

Be it known that I, FRANK E. PFISTER, a citizen of the United States, residing at Oakland, county of Alameda, State of California, have 5 invented certain new and useful Improvements in Gas-Generators for Explosive-Engines; and I do hereby declare the following to be a full, clear, and exact description of the same.

The present invention has for its object, essentially, the utilization of low-grade distillates or oils for the generation of a mixture or gas as an explosive charge for that class of engines known as "gas" or "explosive" engines, the improved generator comprising a casing 15 or shell having working therein a rotatable hollow wheel or drum, means whereby the products of combustion from the explosive-engine are delivered to the interior of the wheel or drum, with mechanism whereby the oil to be 20 volatilized is delivered onto or into oil-receiving receptacles secured to the periphery of the rotatable drum or wheel, and a receiving-reservoir for the generated gas communicating with the interior of the shell or casing.

To comprehend the invention, reference should be had to the accompanying sheet of drawings, wherein—

Figure 1 is an end view in elevation, partly broken away, of the improved generator; and 30 Fig. 2 is a side view in elevation, partly broken away, of the apparatus. Fig. 3 is an enlarged view illustrating the oil-feed supply-pipe and the air-valve.

In the drawings the numeral 1 is used to indicate the shell or casing, within which works the drum or wheel 2. This drum or wheel is a hollow one, the interior thereof being formed into a spiral passage-way 3 by means of the partition-wall 4. The hollow trunnions 5 35 6 work through bearings 7 of the shell or casing, trunnion 5 being connected to the exhaust-pipe 8 by the stuffing-gland 9. The trunnion 6 is connected to the pipe 10 by stuffing-gland 11. This pipe 10 communicates with the cylinder 12, supported above the casing or shell 1. Within the cylinder 12 is arranged the reservoir 13, the same being somewhat smaller than the cylinder 12, so as to leave a heat-space 14 therearound. The reservoir 13 is

thus heat-jacketed, the said reservoir communicating with the interior of the casing or shell 1 by means of the connection 15. The gas as generated within the shell or casing 1 escapes into the receiving-reservoir 13 through the said connection 15. From the gas-reservoir 15 the gas is withdrawn by the operation of the engine (not shown) by means of the suction-pipe 15.

The oil or hydrocarbon to be used for the generation of the gas or explosive vapor is fed into the shell or casing 1 from the pipe 17. The lower end of this feed-pipe is arranged to deposit the oil flowing therefrom into one of the series of pockets or receiving-chambers 18, secured to the periphery of the drum or wheel 2.

To the trunnion 5 is attached a worm-gear 19, which is driven by an intermeshing worm-pinion 20, mounted upon the shaft 21. This shaft is driven from the engine by any suitable connection, whereby the shaft is actuated to drive the worm-gear 19 during the operation of the engine.

The hot products of combustion or exhaust from the engine as carried through the drum 75 or wheel 2 heats the surface thereof and the interior of the shell or casing to a high degree sufficient to volatilize the liquid hydrocarbon held within the receiving-cups, pockets, or receiving-chambers 18 during the rotation of the wheel or drum 2. As the wheel or drum 2 is rotated the liquid hydrocarbon held within the said pockets, cups, or chambers is maintained in an agitated condition.

By the time any one of the pockets, cups, or receiving-chambers reaches the point X within the casing or shell the lighter or volatile portions of the oil or hydrocarbon will have been thrown off, leaving the heavier or worthless portions therein. This residue or 85 worthless portion is discharged from the cups, pockets, or chambers 18 during the continued rotation of the wheel or drum 2 and deposited within the receiving-pit 22, from which it may be withdrawn. This receiving-pit is closed by 90 the face-plate 23.

The feed-supply pipe communicates with the interior of the gas-reservoir by the branch

connection 24, within which works the suction-valve 25. This valve controls the feed-inlet 26 for the oil or hydrocarbon.

With each stroke of the engine a charge of 5 gas is drawn from the reservoir 13 into the explosive-chamber through suction-pipe 16. The suction thus caused is sufficient to overcome the pressure of the valve-spring 27 and to draw the valve 25 inward to open the feed- 10 inlet 26 and permit a charge or given quantity of the oil or hydrocarbon to pass from the supply-pipe 27' into the feed-pipe 17, by which it is conveyed to the interior of the casing or shell 1 and delivered into the cups, 15 pockets, or receiving-chambers 18 of the rotat- ing drum or wheel 2.

Air is supplied to the interior of the shell or casing, which interior shall hereinafter be termed a "mixing-chamber" 28, for inter- 20 mixing with the generated gas by means of the inwardly-moving valve 29. This valve is actuated to admit air by the suction created within the gas-reservoir as a charge is with- drawn therefrom through the suction-pipe 16.

25 The gas within the reservoir 13 is main- tained heated by the hot products of combus- tion circulating within the space 14, which products of combustion escape through the outlet-opening 30.

30 Having thus described the invention, what is claimed as new, and desired to be protected by Letters Patent, is—

1. A gas-generator for explosive-engines, the same comprising a shell or casing, a drum 35 for the hydrocarbon rotatably mounted there- in, means attached to the said drum for receiv- ing the hydrocarbon, means for supplying the hot products of combustion from an engine into and through the drum, and a gas-receiving 40 reservoir which communicates with and re- ceives the gas from the vaporizing-chamber of the shell or casing.

2. A gas-generator for explosive-engines, the same comprising a shell or casing, an in- 45 teriorly-heated drum for the hydrocarbon ro- tatably mounted within the shell or casing, a feed-pipe extending into the shell or casing,

receiving devices attached to the rotatable drum for receiving the hydrocarbon from the feed-pipe, mechanism for imparting rotation 50 to the drum, and a receiving-chamber located beneath the drum for the reception of the heavier or non-volatile portions of the hydro- carbon discharged from the receiving devices of the drum.

3. A gas-generator for explosive-engines, the same comprising a shell or casing, an in- 55 teriorly-heated drum for the hydrocarbon rotatably mounted therein, a feed for the hydrocarbon extending into the shell or casing, 60 receiving devices carried by the drum into which the hydrocarbon is delivered, a heat- jacketed gas-reservoir communicating with the interior of the shell or casing, an air-inlet valve for supplying air into the vaporizing- 65 chamber, and means whereby the products of combustion from an engine are delivered into the drum and from the drum to the heat-cir- culating space of the heat-jacketed reservoir.

4. A gas-generator for explosive-engines, 70 comprising a shell or casing, an interiorly- heated drum rotatably mounted therein, means for imparting rotation thereto, a feed for the hydrocarbon extending into the shell or cas- 75 ing, devices carried by the drum for receiving the hydrocarbon fed into the shell or casing, a receiving-chamber located below the drum into which the heavier or non-volatile portion 80 of the hydrocarbon is discharged from the receiving devices of the drum, a heat-jacketed gas-reservoir communicating with the interior of the shell or casing, means for supply- 85 ing the products of combustion from an engine into and through the drum, and connection whereby the products of combustion are con-veyed to the heat-space of the heat-jacketed gas-reservoir.

In witness whereof I have hereunto set my hand.

FRANK E. PFISTER.
